UNITED STATES PATENT OFFICE.

JAMES WILLIAM GIBSON BROWN, OF MAYFIELD, NEAR NEWCASTLE, NEW SOUTH WALES, AUSTRALIA.

RAILWAY CAR-COUPING OF THE AUTOMATIC TYPE.

1,326,567.

Specification of Letters Patent.

Patented Dec. 30, 1919.

Application filed September 30, 1918. Serial No. 256,256.

To all whom it may concern:

Be it known that I, JAMES WILLIAM GIBSON BROWN, subject of the King of Great Britain and Ireland, residing at "Allen-
dale," Crebert street, Mayfield, near New-
castle, New South Wales, Australia, have
invented certain new and useful Improve-
ments in Railway Car-Couplings of the
Automatic Type, of which the following is
10 a specification.

This improvement relates to horizontal hook and jaw self closing car couplings which are automatically locked closed by a drop key when bumped into coupled position by
15 contact with the coupling of another car, and which are positively unlocked and opened by raising the drop key. It has been devised with the object of providing a short length coupling of rugged construction, not
20 liable to derangement in use, which is adapted to coact with another coupling of uniform design, regardless of a difference (within working range) in the bolster levels of the vehicles fitted therewith respectively,
25 or of the angular position of such vehicles as when located on a curve, and which offers a very small margin of free slack, and which is designed to close and lock automatically without heavy impact of the fel-
30 low-coupling, and to release readily, except while under compression, when the drop key is raised.

In the accompanying explanatory drawings, Figure 1 is a perspective view of the coupling with the hook in open position and the drop key down; this view shows also the decoupling tripper contained in the key, and means for raising it and so raising the key from the side of the track as to
35 relieve shunters from the necessity of entering between vehicles to effect uncoupling; Fig. 2 is a perspective view of the drop key; Fig. 3 is a horizontal sectional plan showing the coupling open; Fig. 4 is a horizontal sectional plan showing the coupling closed and locked; Fig. 5 is a vertical section showing the positions of the various elements shortly after the closing movement of the coupling hook is commenced, when
45 the toe of the coupling hook is just making contact with a latch face in a lateral gap in the drop key; Fig. 6 is a similar section through the jaw showing the drop key about to fall by gravity and engage behind the heel
50 of the coupling hook to chock it in closed
55 of the coupling hook to chock it in closed

position; Fig. 7 is a similar section explanatory of the releasing movement, the tripper being raised by the decoupling gear (Fig. 1) to bring its lug back behind the hook heel and push up the drop key until the 60 tripper and the key come to the position shown in Fig. 8; Fig. 8 is a similar section showing the positions of the elements when the heel of the snatch lug of the tripper which works in a lateral gap in the drop 65 key is engaged with the heel of the hook in the release movement; Fig. 9 is a fragment horizontal section taken on plane 9-9 in Fig. 8; Fig. 10 is a fragment sectional elevational view explanatory of the working 70 position of the tripper lug on the latch face of the hook; and Fig. 11 is a perspective view of the hook shown in the same position, the tripper and its lug being indicated in dotted lines.

The shank 20 of the jaw may be formed in any design appropriate to the draw bar or bolster attachment, which may be a vertical king pin (not shown). The jaw body is recessed (21) to accommodate the foot 32 80 of the hook, and its lateral portions are extended forming horns, the one to form a lug 22 for the vertical pintle pin 23 on which the hook is pivotally carried, and the other to form a lip 24, which serves as a 85 guide to bring the hook claws into full engagement in the closing movement, and thereby to assure the forcing home of the hook foot until its heel 25 is engaged behind the drop key 26. This function will 90 be understood by referring to Figs. 3 and 4. The hook comprising a claw 29, and a foot 32, with a midway pin eye, has a limited range of lateral swing on its pintle 23, determined by the clearance in the jaw lug 95 22 at 27, with the object that the heel 25 of the hook will be knocked by the claw nose 28 of the pair hook on an approaching vehicle in the coupling movement. In that movement the opposed hooks contact, as 100 shown in Fig. 3 and clasp their claws 29, as both close simultaneously to the position shown in Fig. 4. The clearance above and below the lateral extensions of the jaw forwardly of its recessed body portion 21 admits of the engagement of couplings when they are out of horizontal plane as under no circumstances does the claw of the hook 105 enter the recess 21. If the depth of the coupling claw (see Fig. 1) is, for instance, 110

six inches, it is possible to effect coupling within the greatest range of height difference which is found necessary in practice, and to retain effective traction under extreme conditions of relative vertical movement of coupled cars when running on an uneven track. The claw 29 is of curved section with round nose 28; its curves are struck from the corner of the heel 25, and 5 the gullet portion 30 is formed with adequate clearance to accommodate the nose 28 of the engaged coupling claw in the locked position shown in Fig. 4. The foot 32 of the hook is horizontal on its under 10 face, but is formed as a downwardly swept angular curve from heel 25 to toe 31 on its upper face thus forming a latch face, its edge being curved about the center of the pin 23 and its toe extended to give a length of 15 20 face corresponding with the minimum arc of movement required between closed and open positions of the hook.

The hook is locked in closed position by the drop key 26 which has a free sliding fit 25 in a rectangular vertical socket in the jaw, and when dropped with the hook closed its upper solid portion 33 is positioned behind the heel 25 forming an abutment, as best seen in Fig. 4. In the closing movement, the 30 toe 31 enters below the latch face 34 at the top of the lateral gap 35 in the key and the key is raised as the foot passes under said latch face 34 until the heel 25 passes it, whereupon the key drops by gravity and its 35 solid part 33 then forms an abutment for the heel 25 as shown in Fig. 4. The entering position of the toe is seen in Fig. 5, and the locked position is shown in Fig. 7. The lateral gap 35 in the key is located in the 40 path of movement of the hook foot 32, when the key is raised. The closing is thus effected by latch action as the ramp of the foot runs under the key face 34, and lifts the key, which drops to locked position by 45 gravity as soon as the heel 25 passes it.

The decoupling means comprises a tripper bar 36, which is formed with a double ramp face and carries a laterally offset and forwardly projecting snatch lug 37. The tripper bar 36 is freely slidable in a groove 38 in the rear side of the key, and the snatch lug 37 is accommodated in the key gap 35, said gap exposing the middle portion of one side of the key groove 38. The bottom of 50 55 this groove is formed with ramps complementary to the ramps on the face of the tripper bar 36. There is one cam face 39 at the top end of the tripper bar 36 and another 52 behind the snatch lug 37; below 60 the cam face 52 is a concavity 40. On the bottom of the key groove 38 one cam face 41 is formed immediately above the latch face 34, and another 53 to register with the tripper ramp 40, when the tripper bar is very 65 near top position, (see Fig. 8). When

raised the top end of the tripper bar contacts with the head of the key at the top of the slot 38, and when further raised, it pushes the key upward, (see Fig. 8).

The under face 42 of the snatch lug 37 70 is angularly disposed to fit neatly and slide on the ramp face 54 of the hook foot, (see Fig. 10). The top face of the snatch lug is formed with a horn 43, which has an angular rear side 44. The snatch lug horn 75 43 always projects more or less forward of the abutment face of the key 26, and laterally is arranged flush with the key side, so that it does not interfere with the sliding movement of the key in its socket; the tripper bar is in thickness less than half the thickness of the key, and is of less depth than the key groove, and the snatch lug projects forwardly from it as well as laterally, the parts being proportioned so that when the 80 85 trip bar is forward and upward with the key raised and supported by it, as in Fig. 8, which shows the commencement of the release motion, the snatch lug horn face 44, will be pressed forward by its contact with 90 the lower edge of the face 34 and its slipper face 42 will be forced forward over the heel 25 of the hook. A pocket 45 is formed in the key socket to accommodate the snatch lug while it is in this forwardly extended 95 position.

The lower end of the tripper bar is continued below the bottom end of the key and its extension is adapted to be engaged by any appropriate lift gear for effecting decoupling. A gear such as shown in Fig. 1 may be used, where 46 is a transversely disposed shaft, 47 a hand wheel for rocking said shaft, 48 an arm on said shaft, and 49 a slotted hole in the tripper bar 36, in which 100 105 hole the arm 48 may work freely.

The operation is as follows:—

In coupling, starting from the open position of the coupling, Figs. 1 and 3,—another vehicle, fitted with a horizontal hook coupling of the same type or of a type adapted to coact with the coupling herein described, is caused to "bump", thereby clashing the coupling hooks (see Fig. 3). As the couplings come together, they clasp (see Fig. 110 115 4), the hook foot being thus pushed home into the recess 21. In this homing movement the latch face 54 of the hook foot enters at the toe (Fig. 5) below the latch face 34 at the top of the key gap 35, passing 120 through said gap by contact with the key latch face 34, and causing the key to slide upward to the position shown in Fig. 6. On its attaining this position, the heel 25 of the hook foot passes beyond the key latch 125 face 34, and the key being then unsupported by the foot falls by gravity, setting its solid face portion 33 behind the heel 25 as an abutment and preventing outward swing of the hook. The coupling movement is, there- 130

fore, a simple latching movement, the key 26 dropping by gravity behind the heel and securely holding the claw 29 in the clasped position. To decouple, the tripper rod 36 5 is pushed upward from the lower end, preferably by a track side gear, such as shown in Fig. 1. In the lower position (see Figs. 5 and 6) the ramps 41 and 53 push the tripper rod back in the groove 38. The first effect 10 of the lifting action is to bring the forward face of the snatch lug 37 against the back of the hook heel 25. The bottom edge of this heel being eased off a little as shown at 50, holds the snatch lug 37, and the tripper bar 36 backward in the key groove 38, so that the back of the bar bears against the rear side of the socket in the jaw, the horn 43 at the face of the snatch lug standing 15 just clear of the slipper face 34 in the key notch, as best shown in Fig. 9. The upward movement of the tripper bar being continued further, the key being raised with it after its top end has reached the end of the key groove 38, the snatch lug 37 is kicked 20 forward by contact of its face 44 with the toe of the latch face 34, as soon as it has passed over the hook heel 25. The lifting movement is checked by the contacting of the top of the snatch lug with the top end of 25 the pocket 45 in the jaw (see Fig. 8). It will be noted that the ramp faces 39 and 41 and 40 and 53 are riding on each other when the key and the tripper rod are in the lower position (Figs. 5 and 6), so that the snatch 30 lug 37 is retired sufficiently to insure it clearing the lower corner of the hook heel. When it has cleared the heel, the ramps are out of register, and it is then free to move forward as its horn 43 rides over the leading 35 edge of the latch face 34. As soon as the lifting movement of the tripper rod is checked by contact of the horn of its snatch lug with the top end of the pocket 45, the track side gear 46, 47, 48 is dropped. The 40 tripper bar 36, carrying the key 26 with it, now falls by gravity, the latch face 42 of the snatch lug 37 catching over the heel of the hook foot and sliding down over the ramped foot face 54, forcing the hook open by a 45 latch-like action (see Figs. 10 and 11) until its toe 31 is clear, upon reaching which point the tripper rod drops, leaving the snatch lug 50 accommodated in the lower part 55 of the pocket in the key socket, with clearance 55 above it for the hook toe to enter below the slipper face 34, of the key slot 35 to again effect coupling, when a complementary coupling is "bumped" home as before described by shunting two similarly fitted cars together. The drop key 26 is fitted with a button or flange head 51 which prevents the key from falling down through the socket. The trip rod 36 is prevented from falling 60 out of the key slot 38 by the contacting of the snatch lug with the bottom of the socket 65 pocket 55. The key and the tripper rod are, however, removable upwardly when the trip rod is held backwardly to clear the horn of the snatch lug from the head of the socket pocket 45, a clearance 56 being provided in the rear wall of the socket above the pocket 45 to allow the projecting face portion of the snatch lug to pass through it as the key is raised. It will be noted that the coupling cannot be freed by lifting the key upward; it is necessary that the trip rod be raised from below until it forces the key before it up through the socket sufficiently far to remove its solid face 33 from abutment behind the hook heel 25, so that the snatch lug 37 jumps over the hook heel as shown in Fig. 8, and moves downward carrying the key with it as the opening movement of the coupling progresses.

What I claim as my invention and desire to secure by Letters Patent is:—

1. A car coupler comprising a recessed and laterally horned jaw, a horizontal coupler hook pivotally carried midway of its claw and foot by one of the horn jaws, a lock key 90 slidable vertically in a socket hole in the jaw and engageable with said hook foot, a lateral gap in the key with a latch face at its upper part and a ramp face at the top of the hook foot complementary to said latch face and 95 adapted to bear the key upwardly in the closing movement of the foot and permit the key to drop behind the heel of said foot and there form a locking abutment when the hook attains the full closed position, a 100 tripper bar slidable and capable of limited vertical and transverse movement in a vertical groove in said key and having a lateral lug accommodated in the key gap adapted to jump the heel of the hook foot and engage upon the ramp face thereon and hold the key inactive when the tripper bar is 105 pushed upwardly to raise the key sufficiently to offer clearance for said jump movement.
2. In a car coupling of the jaw and horizontal hook type, means for locking and unlocking the hook in the jaw, said means comprising a latch action key, slidably housed in a vertical socket in said jaw and adapted 110 to be raised by the foot of the hook in the closing movement and to drop by gravity behind said foot, and a tripper contained in said key, armed with a lug which engages over the hook foot when the tripper is 115 raised, and so holds the key up, offering clearance for reverse movement of the hook foot in the opening movement of the coupling hook foot.
3. In a car coupling of the jaw and horizontal hook type, means for locking and unlocking the hook in the coupling jaw, said means comprising a latch lift gravity drop key, having a lateral gap, a tripper, a lug carried by the tripper and accommo- 120 125 130

dated in the gap, and a ramped foot on the hook, said key being raised in the closing movement of the coupling by the movement of the ramped foot under a latch face in 5 the lateral gap therein and held open to permit opening of the coupling upon the raising of the tripper and the engaging of the lug of the tripper above said ramped foot.

4. In a locking mechanism for a car coupling of the jaw and hook type, consisting of a gravity drop key with a clearance gap cut in one side of it through which a ramped foot on the coupling hook may pass while bearing upwardly against a latch 10 face on said key, thereby lifting said key 15

out of its path and permitting said key to drop behind it to form an abutment, of a release tripper contacting with said key and carrying a snatch lug which, when the tripper is raised manually and the key lifted by it, engages over said ramped foot and is held up thereby, sustaining the key with the clearance gap therein open behind said foot, thus releasing the hook. 20

In testimony whereof I affix my signature 25 in the presence of two witnesses.

JAMES WILLIAM GIBSON BROWN.
